UNITED STATES PATENT OFFICE

EUGENE R. CARICHOFF, OF SCHENECTADY, NEW YORK, ASSIGNOR TO GENERAL ELECTRIC COMPANY, A CORPORATION OF NEW YORK

CONTACTOR

Original application filed December 1, 1927, Serial No. 237,075. Divided and this application filed October 17, 1928. Serial No. 313,118.

This application is a division of my prior application Serial No. 237,075, filed December 1, 1927.

My invention relates to circuit controlling devices, particularly of the electromagnetically operated type and the present invention comprises various new and useful improvements in the circuit controlling switch mechanism itself and also the magnetic blowout arrangement associated therewith.

Among the principal objects of the invention are to increase the current carrying and arc interrupting capacities of the switch mechanism, and to improve the construction thereof so as to render both manufacture and maintenance of the switch in service relatively simple and inexpensive.

The several improvements of the invention are particularly advantageous when embodied in a multiple pole alternating current contactor such as illustrated in the accompanying drawing, although various features of the invention may be utilized separately in other forms of switches with equal advantage whenever desired.

In the drawings Fig. 1 is a front view of a three pole alternating current contactor embodying the improvements of the present invention in their preferred form. Fig. 2 is a sectional view of the contactor shown in Fig. 1 along the lines 2-2. Fig. 3 is a sectional view of the rotatable shaft which carries the movable switch members and the movable magnetic member of the electromagnet. Fig. 4 is a side view showing the detailed construction of the contact fingers and the magnetic blowout provided for each pole of the contactor with certain parts broken away in order to more clearly illustrate the details of construction.

The contactor shown in Fig. 1 comprises the movable switch members 10, 11 and 12 which are mounted in spaced alinement upon the rotatable shaft 13 to form a three pole switch particularly adapted for alternating current service. The pivotal supports 14 and 15 for the contactor shaft 13 together with the magnetic blowouts 16, 17 and 18 for the movable contacts 10, 11 and 12 and also the operating electromagnet 19 all are mount-

ed upon the base 20. Base 20 preferably is formed of suitable insulating material.

The operating electromagnet 19 is designed to be energized with alternating current and embodies several distinctive and advantageous features of construction that are specifically described and claimed in my previously noted application Serial No. 237,075. As shown in Fig. 2 the operating electromagnet has a stationary frame 21, a movable armature 22, and an operating winding 23. The armature 22 of the electromagnet is mounted upon the arm 25 which is removably secured to the shaft 13 by means of the bolts 36 and a spacing plug 43. It will be observed from Fig. 3 that the shaft 13 is formed of molded insulating material in channel truss shape with a plurality of webs 18' extending transversely between the walls of the channel truss and having the several recesses 54 and cooperating holes 54' located intermediate the webs for removably securing the switch members 10, 11 and 12 in spaced alinement on the center wall of the channel truss. The spacing plug 43 is arranged to fit snugly 75 into one of the end pockets of shaft 13 and provided with suitable holes through which the holding bolts 36 previously referred to are passed. An additional bolt 44 is provided for more firmly securing the plug 43 to 80 the shaft 13 and at the same time fastening the auxiliary switch mechanism 45 to the shaft.

It will be noted in Fig. 3 that the contactor shaft 13 is provided with shoulders at each end with a central opening formed therein to receive the pivotal bearing pins 46 which are secured to the supports 14 preferably by riveting thereto. With the switch shaft 13 formed of molded insulating material this 90 bearing construction requires no oil and will withstand long service without appreciable wear.

The movement of the armature 22 away from the core 21 is limited by the stop 47 95 which is secured at one end by the bolt 28 and preferably is provided with a buffer 48 of a wear resisting and resilient material such as fiber. The stop 47 also carries the clamp 50 which serves to hold the winding 100

spool 24 securely seated upon the middle leg of the core 21. With this construction the removal of the stop 47 by loosening the bolt 28 readily permits the operating winding 23 to be removed for repair.

The construction of the contact fingers and of the magnetic blowout provided for each pole of the contactor is shown more in detail in Fig. 4. From this figure it will be seen that the movable contact finger 51 is carried in overlapping relation upon a supporting arm 52 which is in the form of a flat metal strip and is removably secured at one end to the shaft 13 by the bolt 53. Preferably shallow channels as indicated by the dotted lines 54 in Fig. 3 are provided on the back side of the shaft 13 for anchoring the several contact supporting arms 52. In this way a single bolt 53 serves to hold each supporting arm 52 in proper alignment on the shaft 13. The contact finger 51 also is formed from a metal strip with one end curved up to provide a contact face as shown in Fig. 4. The contact finger 51 has a slot for receiving the guide 55 which is fixedly secured near the free end of arm 52 so as to project at right angles thereto. The guide 55 is of non-circular cross section and the slot in contact finger 51 is of corresponding shape so as to prevent rotation of the finger about the guide. This insures that the finger always is maintained in alignment at the support. The arm 52 also is provided with a pointed pivot pin 56 which fits into a corresponding recess or depression in the contact 51 so as to form a pivotal bearing for the latter.

The projecting end of the guide 55 is formed in T shape and the compression spring 57 is of sufficient diameter to pass freely over the laterally extending tongues at the end of the guide into engagement with the contact finger 51. To maintain the spring 57 under compression, the cup shaped washer 58 is arranged to seat the outer end of the spring 57. As clearly shown in Fig. 1 the washer 58 is provided with an elongated slot which permits the T shaped end of the guide 55 to pass therethrough. Thereupon the washer 58 may be given a half turn to bring the slot out of alignment with the T head of the guide 55. Preferably holding lugs 59 are punched up from the edges of the slot in the washer 58 so as to prevent accidental return of the slot in the washer into alignment with the T head of the guide 55. This interlocking arrangement permits ready removal of the compression spring 57 as well as the contact 51 from the guide 55 in case the contact 51 should become worn or damaged in service. The contact 51 is connected to the stationary terminal 59' by means of the flexible shunt or connector 60.

The stationary contact 61 which cooperates with the contact finger 51 in closing and

opening the circuit controlled by the contactor is removably mounted upon the support 62 which serves as an arc horn and is secured at one end to the base 20 by the bolt 63. The arc horn 62 also is rigidly connected to one end 70 of the blowout coil 64 to support the same adjacent one side of the arc horn. The other end of the blowout coil is connected to the terminal 65 from which the line conductor 66 extends. It will be observed that arc horn 62 is substantially of C shape. The arc horn 62 is of sufficient width as shown in Fig. 1 to almost completely surround the blowout coil 64. The upper free end of the C-shaped arc horn 62 is provided with an upturned projection 67. The arc chute 68 is arranged to be secured in position to restrict the arc path by means of the upturned finger 67 and the curved portion of the arc horn 62. As shown in Fig. 1 the arc chute 68 is formed of spaced apart 85 walls of good insulating material. Suitable spacing lugs 69 and 70 are interposed between the walls forming the arc chute and the bolts which hold the walls together pass through these lugs. The interior surfaces of the walls 90 forming the arc chute are each provided with a curved shoulder 71 adjacent the lug 69. The relation of the lug 69 and the curved shoulder 71 is such that the arc chute fits snugly upon the curved portion of the arc 95 horn 62 with the upturned projection 67 thereon in hooked engagement with the lugs 69 and extending between the side walls of the arc chute. Thus the arc chute 68 is firmly maintained in its proper position to 100 receive any arc which may occur upon the separation of the contact 51 from the contact 61. Furthermore the member 62 serves to support both the blowout coil 64 and the arc chute 68 and also as an arc horn extending 105 entirely along one edge of the arc chute.

The blowout flux set up by the coil 64 is conducted in the region of the arc by means of the laminated magnetic pole pieces 71' which extend from the magnetic core passing 110 through the blowout coil 64. As shown in Fig. 1, the laminated pole pieces 71' extend on either side of the arc chute 68 adjacent to the point of operation of the contacts 51 and 61. In order to maintain the pole pieces 71' in the proper operating position, the guide 72 is secured to the pole pieces and extends into a hole 73 provided in the base 20. The upturned portion 74 of the pole pieces 115 is provided in order to obtain a wider distribution of the blowout flux through the arc-ing region.

With the arc chute constructed as described it will be evident that the arc chute may be 125 readily lifted out of engagement with the support 62 as indicated in Fig. 1 thereby exposing the contact fingers 51 and the contact 61 for inspection and any necessary re-pairs.

The operation of the electromagnetic switch just described will be apparent. Upon energization of the operating windings 23 the movable armature 22 is attracted into engagement with the frame 21 to rotate the shaft 13 and thereby close the switch contacts. Upon deenergization of the operating winding 22 the out of balance weight of the armature 22 and the finger springs insure a quick opening of the switch. The blowout coils and arc chutes associated therewith insure the rapid disruption of any arcs that may occur upon the separation of the contacts.

15 What I claim as new and desire to secure by Letters Patent of the United States is:

1. A switch shaft molded of insulating material in the form of a channel truss provided with a plurality of webs extending 20 transversely between the walls thereof and having means located intermediate the webs for removably securing a plurality of switch elements in spaced apart alignment on the center wall thereof.

25 2. A switch shaft molded of insulating material in substantially channel shape with a plurality of webs extending transversely between the walls thereof and provided with slots and openings on one face thereof for 30 securing a plurality of switch elements in spaced alignment thereon and having cylindrical openings formed in opposite ends thereof for rotatably supporting the switch shaft.

35 3. A contact device for electric switches including a supporting strip having fastening means at one end, a pivot pin intermediate the ends thereof, and a guide projecting from the other end thereof, said guide having a

40 T shaped end, a contact finger having a slot adapted to fit over said T shaped end into non-rotatable sliding engagement with the guide, and a recess located in cooperating relation with said pivot pin to form a pivot bearing, a coiled spring surrounding the portion of said guide projecting through said slot for biasing the contact finger into pivotal engagement with the support, and a washer provided with an elongated slot adapted to interlock with the T shaped end of said guide for removably securing the spring in position.

In witness whereof, I have hereunto set my hand this 16th day of October, 1928.

55 EUGENE R. CARICHOFF.
